[57] CLAIM

The ornamental design for a handle housing for a battery powered string trimmer, as shown and described.

DESCRIPTION

FIG. 1 comprises a perspective view, taken from the left and from the front, of one embodiment of a handle housing for a battery powered string trimmer according to the present invention;

FIG. 2 is a perspective view taken from the right and from the rear thereof;

FIG. 3 is a top plan view thereof;

FIG. 4 is a left elevational view thereof;

FIG. 5 is a bottom elevational view thereof;

FIG. 6 is a front elevational view thereof;

FIG. 7 is a rear elevational view thereof; and,

FIG. 8 is a right elevational view thereof.

The broken line showing of a partial handle shaft is for illustrative purposes only and forms no part of the claimed design.
